Primary Examiner — Wan Laymon*Assistant Examiner* — Clint A Samuel(74) *Attorney, Agent, or Firm* — Brinks Gilson & Lione(57) **CLAIM**

The ornamental design for a storage device blister tray, substantially as shown and described.

DESCRIPTION

FIG. 1 is a front perspective view of a storage device blister tray of my new design;

FIG. 2 is a top plan view thereof; a bottom plan view thereof is an identical image;

FIG. 3 is a front elevation view thereof; a rear elevation view thereof is an identical image;

FIG. 4 is a left side elevation view thereof; and,

FIG. 5 is a right side elevation view thereof.

The broken lines showing in the drawings are for the purpose of illustrating environmental structure and form no part of the claimed design.
